UNITED STATES PATENT OFFICE

160,573

PIANO OR SIMILAR ARTICLE

Alexander P. Brown, Beechhurst, N. Y.

Application November 14, 1949, Serial No. 6,037

Term of patent 14 years

(Cl. D56—9)

To all whom it may concern:

Be it known that I, Alexander P. Brown, a citizen of the United States, residing at Beechhurst, in the county of Queens and State of New York, have invented a new, original, and ornamental Design for Piano or Similar Article, of which the following is a specification, reference being had to the accompanying drawing, forming part thereof.

Fig. 1 is a top plan view of a piano or similar article showing my new design, the top being in closed position;

Fig. 2 is a perspective view thereof;

Fig. 3 is a rear elevational view; and

Fig. 4 is a top plan view, the top being in open position.

The dominant features of my design reside in that portion shown in full lines in the drawing.

I claim:

The ornamental design for a piano or similar article, as shown and described.

ALEXANDER P. BROWN.
